UNITED STATES PATENT OFFICE.

KURT PRAETORIUS, OF DRESDEN, GERMANY.

WALL OF BLOCKS OF WOOD AND SIMILAR MATERIAL.

1,418,464.

Specification of Letters Patent. Patented June 6, 1922.

Application filed November 16, 1921. Serial No. 515,613.

To all whom it may concern:

Be it known that I, KURT PRAETORIUS, a citizen of the German Republic, and residing at Dresden, Germany, have invented certain new and useful Improvements in Walls of Blocks of Wood and Similar Material (for which I have filed an application in Germany November 9th, 1920, No. 40,920), of which the following is a specification.

10 This invention relates to walls of blocks of wood and similar material, which are to replace brick walls, for the purpose of quickly erecting buildings and instantaneously using the same, and its object is to provide improved means by which such walls receive a great rigidity.

According to the invention, in the horizontal ranges of said walls, which are jointed in bondlike fashion, vertical rows of 20 blocks are inserted and located at uniform distances from each other in such a way that each vertical block of one row extends through one horizontal range and engages in shallow recesses of the horizontal block 25 of the next ranges above and below said horizontal range, while the blocks of two adjacent vertical rows are so located that one block of one row lies always opposite to the space between the blocks of the adjacent row.

The vertical rows of blocks form thus parallel supports in said wall, whereby a great rigidity is imparted to the latter.

In the accompanying drawing: Fig. 1 is 35 a front view of a wall embodying the present invention; Figs. 2 and 3 are plan views of two different horizontal ranges of blocks; Fig. 4 is a perspective view of part of the wall; Figs. 5, 6, and 7 show the three dif-

ferent blocks used in erecting the wall; *a* 40 designating a horizontal block, *b* the same with a shallow recess in one horizontal side; *c* a vertical block.

It must be understood that one horizontal range *d* means not only one layer of blocks 45 but also a plurality of directly superposed (joint-upon-joint) layers, for instance two as shown, or three, or more of them, as the case may be: "range" designating always the height of horizontal blocks mounted in bond- 50 like fashion with reference to the next range above or below said range.

What I claim, is:—

In a wall of blocks of wood and similar material, in combination, horizontal ranges 55 of said blocks jointed in bondlike fashion and having shallow recesses in the horizontal sides of some of said blocks, and vertical rows of blocks inserted in said horizontal ranges at uniform distances from each 60 other in such a way that each vertical block extends through one horizontal range and engages in said shallow recesses of the horizontal block of the next ranges above and below said horizontal range, the blocks of 65 two adjacent vertical rows being so located that one block of one row lies always opposite to the space between the blocks of the adjacent row, substantially as and for the purpose set forth.

In testimony whereof I have hereunto set my hand in the presence of two subscribing witnesses.

KURT PRAETORIUS.
